BOBBIN

George H. Magrath, Whitinsville, Mass.

Application December 13, 1932, Serial No. 647,003

3 Claims. (Cl. 242—120)

This invention relates to an improvement in bobbins and its principal object is to provide a bobbin having a spindle-clutching device for holding the bobbin firmly in fixed position during the winding and/or spinning operation, which device may either form an integral part of the bobbin or be readily assembled therewith, and which is of simple construction, economical to manufacture and efficient and reliable in operation.

Further objects relate to the construction of my improved bobbin and will be apparent from a consideration of the following description and accompanying drawing which shows different embodiments of the invention chosen for the purpose of illustration.

In the drawing:

Fig. 1 is a longitudinal sectional view of a bobbin constructed in accordance with the present invention and shown in operative position on a spindle of the type generally used in spinning operations;

Fig. 2 is a fragmentary side elevation of the bobbin;

Fig. 3 is a bottom plan view thereof;

Fig. 4 is a fragmentary side elevation, partly in section, of a bobbin embodying a modified construction;

Fig. 5 is a bottom plan view of the bobbin shown in Fig. 4; and

Fig. 6 is an elevation of the spindle-engaging bushing.

The bobbin shown in Figs. 1 to 3 comprises an elongate cylindrical member having the usual body portion 1, terminating at one end in an enlarged butt portion 2 and having an axial bore 3 which extends the entire length of the bobbin. The butt portion is provided with a plurality of spaced, longitudinally extending, radially disposed, peripheral slits 5 which extend through the entire thickness of the butt and body portions and define a plurality of depending, radially flexible, segments 6. A reinforcing ring or ferrule 7 is circumposed about the body portion 1 adjacent to the ends of the slits 5 to strengthen the body portion and prevent any danger of splitting.

The outer periphery of the butt portion is provided with circumferentially extending grooves 8 which receive annular spring members here shown as coil tension springs 9. Preferably three such springs are employed, although one may suffice, it being understood that the invention is not limited to the particular type of spring or the number that may be used. The springs 9

normally exert a uniformly distributed contractive force on each of the segments and yieldingly oppose outward radial movement thereof.

When the bobbin is placed over the blade of a spindle 10, as shown in Fig. 1, the butt portion 60 seats upon the upper end of the whirl 11 which is provided with a flat shoulder portion, here shown as an annular collar 12 having a press fit about the whirl and conical neck 13. If desired, the spindle may be made with a flat shoulder portion integral with the whirl, thus dispensing with the use of the collar 12. The diameter of the upper part of the neck 13 is approximately the same as that of the bore of the bobbin and at the lower end its diameter is appreciably greater so that 65 when the bobbin is seated on the shoulder 12 the segments 6 are flexed outwardly against the action of the springs 9 and consequently firmly grip the periphery of the neck and thereby hold the bobbin in position.

It will be noted that the collar 12 not only provides a firm seat for the bobbin, but furthermore, cooperates with the clutching segments 6 to hold the bobbin in a definite fixed position relative to the whirl and range of travel of the yarn guiding devices, thus overcoming the necessity of making readjustments of such devices before winding each bobbin as is usually required with the prior constructions wherein the bobbin is forced over the spindle so that the butt portion 80 wedges about the neck and does not assume any definite or fixed position relative to the whirl or yarn guiding devices. Moreover, with the present construction there is no danger of the bobbin losing its grip on the spindle during the winding 85 operation, or vibrating out of proper position, and consequently the winding operation may be carried out more accurately and at a greater speed than heretofore possible.

In the embodiment shown in Figs. 4 to 6 the 95 butt portion 2 is provided with an enlarged axial bore in which a bushing 15 is concentrically disposed, the bushing being retained therein by a pressed fit against the inner periphery of the bobbin, as shown in Fig. 4. The bushing is preferably of metal and is provided with a plurality of depending, radially flexible, resilient segments or fingers 16 having outwardly flaring ends 17 which are spaced inwardly from the end of the butt portion of the bobbin to provide a slight 100 clearance so that the bobbin may be seated on the spindle without interfering with the flexing movement of the segments. The bushing 15 and butt portion define an annular recess 18 which provides sufficient clearance between the seg- 110

ments and the inner walls of the butt portion to permit an unrestrained flexing movement of the segments. An annular spring 20, composed about the segments 16, seats upon the projecting end portions 17 as shown in Fig. 4 and yieldingly opposes outward radial movement of the segments as in the previously described embodiment.

Although the spring 20 is herein shown as an annular coil spring, it is to be understood that other means may be provided for yieldingly restraining the outward movement of the segments such for example as a resilient split ring. If desired, the bushing 15 may be of any material capable of providing spindle-engaging segments possessing more or less resiliency and sufficient stiffness yieldingly to oppose outward flexing movement so that the bobbin may be firmly held in place without the use of the spring 20 or its equivalent.

While I have shown and described different embodiments of the invention, it is to be understood that the present disclosure is for the purpose of illustration only and that various changes in shape, proportion, and arrangement of parts, as well as the substitution of equivalent elements for those herein shown and described may be made without departing from the spirit and scope of the invention as set forth in the appended claims.

I claim:

1. A bobbin comprising a tubular member having an enlarged axial bore in one end, and clutching means at said end for frictionally engaging a spindle, said means comprising a tubular bushing disposed within said bore and defining an annular recess, said bushing being secured at one

end to the bobbin and having a plurality of depending radially flexible fingers coaxial with said bore and spaced from the inner periphery of the bobbin, and an annular spring disposed in said recess and engaging the free ends of said fingers yieldingly to oppose outward radial movement thereof.

2. A bobbin comprising a tubular member having an enlarged axial bore in one end, and clutching means at said end for frictionally engaging a spindle, said means comprising a tubular bushing concentrically disposed within said bore and defining an annular recess, said bushing being secured at its upper end within the bore and having a plurality of depending radially flexible segments spaced from the inner periphery of the bobbin and provided with outwardly extending end portions, and an annular spring seated upon the end portions of said segments within said recess for yieldingly opposing outward radial movement of said segments.

3. In a spinning machine, the combination with a rotary spindle having a blade and a whirl mounted on the blade, the whirl having a neck concentric with the blade and a flat shoulder portion surrounding the neck, of a bobbin comprising an elongate cylindrical member having a butt portion seated on said shoulder portion, said butt portion having an enlarged axial bore, and clutching means secured to said butt portion for frictionally engaging a spindle, said means comprising a tubular bushing secured at one end within said bore and having a plurality of radially flexible segments circumferentially disposed within said bore in spaced relation to the inner periphery of said butt portion.
